PARTING MEANS FOR LOOMS

Edward C. Nichols, Upton, Mass., assignor to
Draper Corporation, Hopedale, Mass., a corpora-
tion of Maine

Application October 10, 1934, Serial No. 747,753

6 Claims. (Cl. 139—264)

The present invention pertains to automatic looms of the bobbin changing type and has more particular reference to the thread parting and clamping devices mounted on the shuttle feeler of such looms.

Looms of the type mentioned are commonly provided with a shuttle feeler which is connected with the filling replenishing mechanism in such manner as to be swung rearwardly, toward the lay, to feel for an improperly boxed shuttle. The shuttle feeler operates to prevent filling replenishment when it detects that the shuttle is not fully entered into the shuttle box. It is also common practice to provide the shuttle feeler with thread parting and clamping means, including parting and clamping blades pivoted on the shuttle feeler, for parting the outgoing filling end between the shuttle and the selvage, and clamping the part thereof which extends to the cloth selvage. Such blades are usually provided with a depending heel adapted to be struck by the lay for closing the blades.

Difficulty has been experienced in properly timing the operation of the prior parting and clamping devices of the type just described. More specifically, if the devices are operated too early in the loom cycle they will part the filling thread on every call for replenishment, even though the shuttle may be improperly boxed and the call accordingly revoked. On the other hand, if the devices operate late the outgoing end may be broken by the replenishing operation and thus removed from the field of action of the parter before the latter has operated. Thus, the timing of the closing of the parting and clamping blades must be quite accurate. Prior to the present invention there was no way in which such timing could be accurately adjusted.

Accordingly, it is the principal object of the present invention to provide in a device of the class described, thread parting and clamping members which are pivoted on a shuttle feeler, a lay-engaging plate on the members, and means for accurately adjusting the plate to thereby vary the timing of the closing of the parting and clamping members.

Other objects will become apparent as the description proceeds.

In the preferred embodiment of the invention the adjustable plate is mounted on a depending heel on the parting and clamping blades, the plate being mounted in the plane of the blades so that the edge of the plate is struck by the lay for closing the blades. The plate is mounted for adjustment along a line which extends at

an acute angle to the direction of movement of the lay. This adjustment is very accurate, and is comparatively free from any tendency to loosen under the impact of the lay. This latter feature is of material importance for obvious reasons.

For detailed disclosure of the said preferred embodiment reference may be had to the accompanying drawing, of which:

Fig. 1 is a perspective view, partly in section, of the said embodiment;

Fig. 2 is a side elevation of the parting and clamping devices; and

Fig. 3 is a plan view of the same.

The loom to which my invention has been applied is largely of conventional design. There is accordingly illustrated on the drawing only so much of the loom as is necessary to an understanding of the invention. There is shown, Fig. 1, a part of the lay 1 and the front box plate 2 of the right hand shuttle box. The lay is adapted to be reciprocated toward and from the front of the loom in the usual manner, and the shuttle 3 is adapted to be picked along the lay and received at each end of its flight in a suitable shuttle box.

The shuttle feeler 4 is pivoted on a stud 5 in a bracket 6 which is adapted to be supported by the loom frame (not shown). The normal, or retracted, position of the shuttle feeler is clockwise from the position of Fig. 1 and the shuttle feeler is moved upwardly and rearwardly into the feeling position of Fig. 1 only upon a call for filling replenishment. The shuttle feeler is so moved by an arm 7 engaging pin 8. A knife opening device 9 is supported from the bracket 6, and a revoking connection 10 extends from the shuttle feeler to other mechanism not shown.

A fixed parting blade 11 and a fixed clamping blade 12 are supported on a pivot bolt 13 which extends through the shuttle feeler. The fixed blades 11 and 12 are held from pivoting on the bolt 13 as by means of a pin 14 in the shuttle feeler. Movable parting and clamping members are conveniently comprised of parting blade 15 and clamping blade 16 both of which are pivoted on the bolt 13. The movable blades are opened by the device 9 as the shuttle feeler moves rearwardly and closed by the lay as will hereinafter appear. A spring washer 17 may be positioned beneath the head of bolt 13 for yieldingly pressing the parting and clamping members together.

All of the parts of the shuttle feeler mechanism, and all of the parting and clamping device thus far described, are old and well known in the art. They are of the present invention.

only in that certain of them are desirable forms of elements in the combination defined in the appended claims.

The parting and clamping members 15 and 16 are shown as having a depending heel at their forward end which heel may be formed in part by a depending portion 18 of the members themselves and in part by a heel plate 19 fixed thereto. However the heel is formed, it constitutes the means through which the lay closes the parting and clamping members. It will be apparent from the drawing that the closing of these members substantially before the lay reaches front center would result in the outgoing filling thread *t* being parted before the shuttle feeler had performed its function. Thus, the thread would be parted even though the call for replenishment were subsequently revoked, which constitutes a defect in the weaving operation. Defective operation would also result from the delaying of the parting operation until the lay has reached front center, for at such time the exhausted bobbin (not shown) has been ejected from the shuttle which would result in an uncut thread *t* being stretched, probably to the breaking point.

The present invention provides means whereby the timing of the closing of the clamping and parting members may be adjusted to a nicety, thereby eliminating both of the aforementioned causes of defective loom operation. To this end, the lay does not strike the heel piece 18, 19 directly but strikes the rearward edge of a plate 20 which is adjustably secured to the heel. The plate is positioned parallel to the clamping and parting members. Preferably, the plate is not adjustable in a horizontal direction, which is the direction of movement of the lay, but along a path inclined to such direction. The plate 20 of the specific embodiment shown on the drawing is provided with parallel slots 21, 22 which are inclined downwardly and rearwardly. The opener pin 23 passes through the upper slot 21 and a securing bolt 24 passes through the other slot. The bolt and pin are relatively fixed in the heel 18, 19. The rearward sides of the slots form cam surfaces engaging abutment surfaces constituted by the pin and bolt. In such construction the impact of the lay is transmitted to the heel in a direction at an acute angle to the cam surfaces of the slots. The angle may be such that there is practically no tendency for the lay to drive the plate out of adjustment, and the clamping or securing device, as bolt 24, accordingly need not be so large as to be impracticable.

While the use of a pin and slot connection, such as that just described, is desirable in that it confines the plate 20 to rectilinear adjustment and thereby facilitates such adjustment, it will be apparent that the invention is not limited to this particular type of connection.

Having fully disclosed the preferred embodiment of my invention, I claim:

1. In a shuttle feeler thread parter and clamp, the combination of a lay, a shuttle feeler, parting and clamping members pivoted to said shuttle feeler, a depending heel on said members, said

heel having a plate adapted to be struck by the lay for closing said members, and means for adjusting said plate toward and from the lay for varying the time of closing of said members.

2. In a shuttle feeler thread parter and clamp, the combination of a lay, a shuttle feeler, parting and clamping members pivoted to said shuttle feeler, a depending heel on said members, a plate on said heel parallel to said members and adapted to be struck by the lay for closing the said members, an adjustable connection between said plate and heel permitting adjustment of the plate rectilinearly in a direction inclined to the direction of movement of the lay, and means for securing said plate in adjusted position. 10

3. In a shuttle feeler thread parter and clamp, the combination of a lay, a shuttle feeler, parting and clamping members pivoted to said shuttle feeler, a depending heel on said members, a plate on said heel parallel to said members and adapted to be struck by the lay for closing the said members, an adjustable connection between said plate and heel consisting of a pin-and-slot connection wherein the slot extends at an acute angle to the direction of movement of the lay, 20 and means for securing said plate in adjusted position on said heel.

4. In a shuttle feeler thread parter and clamp, the combination of a lay, a shuttle feeler, parting and clamping members pivoted to said shuttle 30 feeler, a depending heel on said members, a plate on said heel parallel to said members and adapted to be struck by the lay for closing the said members, said plate and heel being provided one with an abutment surface and the other with a 35 cam surface extending at an acute angle to the direction of movement of the lay, thereby providing for adjustment of the plate rectilinearly in the direction of said cam surface, and means for securing said plate in adjusted position on 40 said heel.

5. In a shuttle feeler thread parter and clamp, the combination of a lay, a shuttle feeler, parting and clamping members pivoted to said shuttle feeler, a depending heel on said members, a plate on said heel parallel to said members and adapted to be struck by the lay for closing the said members, said plate being provided with a slot 45 extending downwardly and rearwardly at an acute angle to the direction of movement of the lay, a pin in said heel engaging in said slot and along which said plate is adjustable, and means for clamping said plate in adjusted position on 50 said heel.

6. In a shuttle feeler thread parter and clamp 55 for looms having a lay, the combination of a shuttle feeler, parting and clamping members pivoted to said shuttle feeler, a depending heel on said members, a pin projecting laterally from said heel, means engaging said pin for opening 60 said members, a plate on said heel parallel to said members and adapted to be struck by the loom lay for closing the members, said plate being provided with parallel downwardly and rearwardly inclined slots, said pin engaging in one 65 of said slots, and a clamping device passing through said heel and the other of said slots.

EDWARD C. NICHOLS.
